UNITED STATES PATENT OFFICE.

ALFRED L. SOHM, OF CHICAGO, ILLINOIS, ASSIGNOR TO SOHM ELECTRIC COMPANY, OF CHICAGO, ILLINOIS, A CORPORATION OF ILLINOIS.

PENDULUM.

1,394,690.

Specification of Letters Patent.

Patented Oct. 25, 1921.

Application filed May 5, 1919. Serial No. 294,783.

To all whom it may concern:

Be it known that I, ALFRED L. SOHM, a citizen of the United States, residing at Chicago, in the county of Cook and State of Illinois, have invented a certain new and useful Improvement in Pendulums, of which the following is a full, clear, concise, and exact description, reference being had to the accompanying drawings, forming a part of this specification.

10 My invention relates to pendulums.

More particularly my invention relates to pendulums such as are employed in connection with clocks and the like for properly regulating the escapement thereof.

The usual clock pendulum generally comprises a wood or metallic pendulum rod suspended so as to move freely about its point of suspension and having a suitable weight-20 ed member or bob attached to its lower end. As well understood by those skilled in the art, the usual clock is nothing more than a pendulum with suitable means for registering the number of oscillations thereof and 25 means such as a spring wherein sufficient energy is periodically stored to counteract the retarding effects of friction and the resistance of air.

I have observed that in regulating clocks 30 in order to compensate for temperature changes and the like, the usual and most convenient manner of making such adjustment is by adjusting the length of the pendulum, that is by either shortening or 35 lengthening the same. It is therefore desirable to have the weighted member or bob adjustably mounted on the pendulum rod. Attempts to meet this requirement have resulted in numerous complex devices.

40 My invention aims to provide a pendulum of simple and inexpensive construction which is capable of quick and easy assembly, may be quickly and easily adjusted and is effective in operation.

45 In accordance with the teachings of my invention I have provided a pendulum which may be quickly assembled or readily adjusted without the use of a wrench, pliers, screwdriver or the like, the weighted member or 50 bob being effectively held at all times against displacement regardless of its position on the pendulum rod.

Other aims of my invention will appear from the following detailed description,

taken with an inspection of the accompanying drawings, in which—

Figure 1 is a rear elevational view of a pendulum embodying my invention,

Fig. 2 is a vertical sectional view taken on the line 2—2 of Fig. 1, and

Fig. 3 is a horizontal sectional view taken on the line 3—3 of Fig. 1.

Referring to the drawings, my improved pendulum comprises the usual pendulum rod 1 having a flat circular metallic disk 2 adapted for mounting upon its lower end. The pendulum rod 1 which may be formed of either wood or metal, preferably of wood in order to approach as nearly as possible the simple pendulum, is adapted to be suspended as, for instance, from the verge or escapement shaft of the clock. In this case the escapement shaft of the clock is adapted for oscillating freely with the pendulum.

The rear face 3 of the bob 2 is provided with a groove or channel 4 which extends diametrically thereacross, as shown in Figs. 1 and 2. The groove or channel 4 is adapted for receiving the lower end of the pendulum rod 1, the opposing shoulders 5 and 6 of the groove serving to maintain the pendulum rod 1 vertically alined therein. A strap 7, preferably formed integral with the bob 2, although it may be a separate piece suitably bolted to the bob if so desired, is bridged across the groove or channel 4 and serves together with a suitable spring bridge 8 to retain the bob securely in place on the pendulum rod. The strap 7 is preferably formed flush with the rear face 3 of the bob and extends across the groove or channel 4 at right angles thereto and at substantially the center thereof, the groove or channel 4 reaching its greatest depth at this point due to the convex rear face 3 of the bob.

Thus upon inserting the pendulum rod 1 into the groove or channel 4, sufficient space, as shown in Figs. 2 and 3, is thereby allowed between the strap 7 and the pendulum rod 1 for the reception of the bridged spring retaining member 8.

The center of the bridged spring retaining member 8 is provided with a depressed portion 9 for receiving the strap 7 when the bridged spring is sprung thereunder. The opposite ends of the bridged spring retaining member 8 are adapted for engaging the

pendulum rod 1 at the points 10 and 11 respectively, the extreme ends being bent upwardly from these points of engagement so that the bridged spring 8 may be moved 5 freely along the pendulum rod when so desired. The opposite ends of the bridged spring retaining member 8 are inclined upwardly from its points of engagement with the pendulum rod to the depressed portion 10, the height of the bridge thus formed being such that it can be sprung under the strap 7, the opposing shoulders 12 and 13 formed by the depression 9 engaging the opposite edges of the strap 7 and thereby preventing 15 displacement of the bob 2. When the bridged spring retaining member 8 is sprung into position under the strap 7 as shown in Fig. 2 it will engage the pendulum rod 1 at the points 10 and 11 respectively 20 and thereby create sufficient friction between the pendulum rod and the bottom of the groove or channel 4 to prevent any but intentional movement of the bob 2 along the shaft 1.

25 If it is desired to adjust the length of the pendulum in order to regulate the clock the bob 2 is moved either upwardly or downwardly along the pendulum rod 1 against the frictional engagement between the rod 30 1 and the bottom of the groove 4, this frictional engagement not being sufficient to prevent such movement, although it is sufficient to prevent accidental slipping or other unintentional movement of the bob along the rod 1. The bob 2 is moved either upwardly or downwardly along the pendulum rod 1, accordingly as to whether the speed of the 35 clock is to be increased or decreased, as well understood by those skilled in the art. Upon 40 moving the bob 2 to the desired position on the pendulum rod 1 and then releasing the bob it will be effectively held in place by the bridged spring retaining member 8, which upon being sprung beneath the strap 7 is 45 constantly in frictional engagement with the pendulum rod. For making fine adjust-

ments it is apparent that the pendulum rod 1 could be provided with a suitable scale, a pointer being provided on the bob 2 for readily indicating the amount of movement 50 of the bob when the same is adjusted.

It will now be apparent that I have provided a pendulum of extremely simple and inexpensive construction which is effective in operation and although I have described 55 my invention in connection with the details of a particular embodiment, I do not intend thereby to limit the invention to such details, as I am aware and contemplate that modifications and changes may be made without departing from the invention which is set out in the appended claims.

I claim:

1. In combination, a pendulum rod, a bob having a groove therein, adapted for the reception of said pendulum rod, a bridge member extending across said groove and a spring retaining member yieldingly engaged between the pendulum rod and said bridge member for preventing free movement of 70 said bob.

2. In combination, a pendulum rod, a bob having a groove in one of the faces thereof for the reception of said pendulum rod, a bridge member extending across said groove 75 a spring retaining member arranged in said groove between the pendulum rod and said bridge member, said spring retaining member having a depressed portion therein for co-operating with said bridge member, to 80 prevent unintentional displacement of the spring.

3. In combination, a pendulum rod, a bob, and a spring retaining member sprung between the pendulum rod and the bob to prevent free movement of the bob, said spring retaining member being held against displacement by its yielding engagement between the pendulum rod and the bob.

In witness whereof, I hereunto subscribe 90 my name this 28th day of March A. D. 1919.

ALFRED L. SOHM.
